YARN DYE TUBE

Robert L. Burchette, Jr., 570 El Paso St.,
Spartanburg, S.C. 29303

Filed Dec. 22, 1972, Ser. No. 317,758

Term of patent 14 years

Int. Cl. D15—08

U.S. Cl. D47—5

FIG.2

FIG.1

FIG. 1 is an elevational view of the yarn dye tube showing my new design, with each 90 degree view being identical.

FIG. 2 is a cross sectional view of the yarn dye tube as shown in FIG. 1 and taken along line II—II.

I claim:

The ornamental design for a yarn dye tube, substantially as shown and described.
